UNITED STATES PATENT OFFICE.

MINNA WEZEL, OF BROOKLYN, NEW YORK.

DESIGN FOR A CHEWING-GUM TABLET.

SPECIFICATION forming part of Design No. 26,915, dated April 13, 1897.

Application filed February 23, 1897. Serial No. 624,728. Term of patent 7 years.

To all whom it may concern:

Be it known that I, MINNA WEZEL, a citizen of the United States, residing at Brooklyn, in the county of Kings and State of New York, have invented and produced a new and original Design for a Tablet for Chewing-Gums, of which the following is a specification, reference being had to the accompanying drawings, forming part thereof.

- Figure 1 is a front elevation of my design. Fig. 2 is a central section on the line 2 of Fig. 1.

The design is intended especially for use in connection with the manufacture of chewing-gum, though it is adapted to lozenges, candy, and confections in general.

The leading features of my design consist in a disk-shaped web having an enlarged circumferential rim resembling a tire, a central opening, and a raised rim around said opening, ribs connecting the circumferential with the inner rim.

My design for a tablet for chewing-gum, confections, &c., is in the form of a wheel comprising a disk-shaped web *a* and a circumferential rim *b*, which conveys the idea of a tire. A series of radial ribs *d* connect the said circumferential rim *b* with an interior rim *e*, which extends around a central opening *c* of the web.

The design is identical on both sides, as shown in Fig. 2.

Having thus described my invention, what I claim is—

The design for a tablet for chewing-gum, confections &c. substantially as shown and described.

In testimony that I claim the foregoing as my invention I have signed my name in presence of two subscribing witnesses.

MINNA WEZEL.
